INSTEP BANDAGES**Gustav Wüstemann, Basel, Switzerland, assignor to Franz Jahrstorfer, Basel, Switzerland****Application November 17, 1953, Serial No. 392,724****Claims priority, application Switzerland November 25, 1952****4 Claims. (Cl. 36—8.5)**

The present invention relates to an instep bandage and more particularly to an instep bandage which supports the instep during walking without compressing the sole of the foot adjacent the instep.

In instep bandages according to the prior art, the bandage which effectively binds the instep is so constructed that the sole of the foot is cramped and compressed during walking.

It is an object of the present invention to overcome the disadvantages of the prior art.

It is a further object of the present invention to provide an instep bandage which presents a smooth walking surface while at the same time maintaining the instep bound securely.

Another object of the present invention is to provide an instep bandage which can be constructed and mass-produced easily and inexpensively.

Yet another object of the present invention is to provide an instep bandage which can be inserted into a shoe with a minimum distortion of the shape of the foot-receiving cavity of the shoe.

A further object of the present invention is to provide an instep bandage which is easily applied to and removed from the foot.

With the above objects in view, the present invention mainly consists in an instep bandage having a half-sole portion and an elongated flexible strap portion which are bendable relative each other about a bending axis substantially coincident with the rear edge of the half-sole portion and in which the end portions of the strap portion encompass the instep of a foot. The central portion intermediate these end portions cooperates with the half-sole portion to provide a smooth continuous walking surface for the sole of the foot while the inner faces of the strap portion are smooth and present a continuous surface in supporting the instep of the foot.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a side view showing one embodiment of the instep bandage of the present invention located in a shoe and encompassing an instep;

Fig. 2 is a top view of the present invention; and

Fig. 3 is a developed top view of the device shown in Fig. 2.

With reference to the drawings, Fig. 1 shows an instep bandage, indicated generally by the numeral 27, located in a shoe 1 and encompassing the instep of a foot 1a.

The instep bandage 27 includes an elongated half-sole 2 having a supporting face 12 and a rear edge 2a extending transversely to the length a of the half-sole 2.

The instep bandage 27 includes also an elongated strap portion 25 having a width w and a length s . The strap

2

portion 25 includes opposite end portions 3 and 4 and a central portion 15 therebetween. The strap portion 25 has opposite inner and outer faces, the inner face including portions 13, 14 and 15c, respectively associated with the portions 3, 4, and 15.

As shown in Fig. 3, the portions 3, 4 and 15 have lengths, respectively, as indicated by e_1 , c , and e_2 , so that the overall length of the strap portion 25 is s .

The length of the central portion 15 of the strap portion 25 is substantially equal to the length of the rear edge 2a of the half-sole portion 2, as shown by c in Fig. 3.

A side edge 15s of the central portion 15 is coincident with the rear edge 2a of the half-sole portion 2 so that the half-sole portion 2 extends transversely to the strap portion 25.

The inner face of the strap portion 25 is flush with the supporting face 12 of the half-sole portion 2. The strap portion 25 and the half-sole portion 2 are bendable relative each other about a bending axis I—I substantially coincident with the rear edge 2a of the half-sole portion 2.

The strap portion 25 is made of a flexible material so that the end portions 3 and 4 thereof may be brought toward each other and be secured to each other so as to encompass the instep of the foot 1a positioned on the supporting face 12 of the half-sole portion 2.

By virtue of the above arrangement, the forward part of the foot 1a rests upon a continuous surface constituted by the supporting face 12 of the half-sole portion 2 and by the portion 15c of the inner face of the strap portion 25. Also, the portions 13, 14 and 15c of the inner face of the strap portion 25 form a continuous surface which will be in contact with the instep of the foot 1a while the end portions 3, 4, encompass the same. It will be seen that the strap portion 25 may be bent relative to the half-sole 2 about the bending axis I—I during walking movement of the foot.

Sets of mated holes 7 and 8 are formed in the instep portion and in the shoe 1, respectively, for receiving a shoe lace 8 which passes through both sets of holes to hold the bandage 27 securely in position around the instep of the foot 1a.

The portions 3, 4 of the instep portion 25 may be formed of leather or other flexible material. These portions 3, 4 may also have the outer surfaces thereof covered by a lining 6, of leather or other material.

Cushion means 5 are advantageously adhesively secured on the under surface of the half-sole portion 2. The cushion means 5 is preferably a layer of foam latex 50 which prevents slipping inside the shoe.

In one embodiment of the present invention, the half-sole portion 2 and the strap portion 25 are formed integrally with each other. In other embodiments, the portions 2 and 25 are connected to each other by stitching, adhesive or other means.

It will be understood that each of the elements described above, or two or more together, may also find a useful application in other types of instep bandages differing from the types described above.

While the invention has been illustrated and described as embodied in instep bandage adapted to be interlaced with a shoe, it is not intended to be limited to the details shown, since various modifications and structural changes may be made without departing in any way from the spirit 60 of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and, therefore, such adaptations should and are intended

to be comprehended within the meaning and range of equivalence of the following claims.

What is claimed as new and desired to be secured by Letters Patent is:

1. An instep bandage adapted to be inserted into a shoe and composed of an elongated half-sole having a supporting face and a rear edge extending transversely to the length of said half-sole, and an elongated strap portion having opposite faces and also having opposite end portions and a central portion therebetween, the length of said central portion being substantially equal to the length of said rear edge, a side edge of said central portion being coincident with said rear edge of said half-sole so that said strap portion extends transversely to the length of said half-sole, one of said faces of said strap portion being flush with said supporting face of said half-sole, said strap portion and said half-sole being bendable relative to each other about a bending axis substantially coincident with said rear edge, and said strap portion being made of a flexible material so that said end portions thereof may be brought toward each other and be secured to each other so as to encompass the instep of a foot positioned on said supporting face of said half-sole, whereby the forward part of a foot may rest upon a continuous surface constituted by said supporting face 25

of said half-sole and by that portion of said one face of said strap portion which is associated with said central portion thereof, whereby those portions of said one face of said strap portion which are associated with said end portions thereof are in contact with the instep of the foot while said end portions encompass the same, the last-mentioned portions of said one face forming a continuous surface with the remainder of said one face, and whereby said strap portion may bend relative to said half-sole about said bending axis during walking movement of the foot.

2. An instep bandage as defined in claim 1, and cushioning means on the undersurface of said half-sole.

3. An instep bandage as defined in claim 1 wherein said cushioning means is a layer of foam latex.

4. An instep bandage as defined in claim 1 wherein said half-sole and said strap portion are integral with each other.
